UNITED STATES PATENT OFFICE.

THOMAS C. DUNCAN, OF ST. JOSEPH, MISSOURI.

TONGUE-TRUCK.

1,251,356.

Specification of Letters Patent. Patented Dec. 25, 1917.

Application filed October 13, 1916. Serial No. 125,478.

To all whom it may concern:

Be it known that I, THOMAS C. DUNCAN, a citizen of the United States, residing at St. Joseph, in the county of Buchanan and State of Missouri, have invented new and useful Improvements in Tongue-Trucks, of which the following is a specification.

This invention relates to tongue trucks, and it has particular reference to an improved tongue truck adapted to be used in connection with grain binders and the like.

The invention has for its object to produce a tongue truck including a tongue, a supporting wheel for the same and a resilient connection between the wheel and the tongue.

A further object of the invention is to produce a tongue truck including an adjusting lever and a connection between said lever and the evener to which the draft is attached, whereby the application of the draft will have a tendency to relieve the pressure of the tongue on the necks of the draft animals.

A further object of the invention is to produce a tongue truck and a connection between the same and the binder to which it is applied, whereby the raising or lowering of the binder frame will so actuate the adjusting lever of the tongue truck that the binder frame will be maintained in a level position.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings,—

Figure 1 is a side elevation of the improved tongue truck.

Fig. 2 is a transverse sectional view taken on the line 2—2 in Fig. 1.

Fig. 3 is a top plan view.

Fig. 4 is a side elevation of the rear portion of the tongue truck showing also a portion of a binder frame with which it is connected.

Fig. 5 is a view similar to Fig. 4, but showing the parts in a different position.

Corresponding parts in the several figures are denoted by like characters of reference.

The tongue 15 is provided at its rear end with a vertical slit or kerf 16 for the reception of a bracket member B having a straight forward portion 17 and an arcuate rear portion 18, the straight forward portion being fitted in the slit 16 where it is firmly secured by transverse bolts 19. The arcuate portion 18 is curved downwardly and rearwardly with respect to the tongue, and it is provided at its rearward end with lugs 20 for the passage of the pivot member 21, whereby it is connected with the binder frame, shown at H. The forward portion of the bracket member is provided with laterally extending lugs 22 for the passage of a vertically movable shank 23, the lower end of which has an enlarged head or bearing member 24. 25 is a crank arm having at its lower end a spindle 26 on which a caster wheel 27 is supported for rotation; the upper end of the crank arm 25 has a spindle 28 that pivotally engages the head or bearing member 24, said spindle being provided at one end with an arm 29. A spring 30 that is coiled about the bearing member 24 has one end extended in engagement with the arm 29, the other end of said spring being suitably attached to or connected with the head or bearing member 24 so that the tension of the spring will be exerted to swing the crank arm carrying the wheel 27 in a downward direction, the movement of the crank arm being limited by stop members 31. By the construction shown the weight of the tongue will have a tendency to tension the spring 30 and, conversely, the spring will have a tendency to support the weight of the tongue and related parts, affording a resilient support for the same.

An adjusting lever L, which is fulcrumed on the arcuate portion 18 of the bracket member B at 32, has a forwardly extending arm 33, a rearwardly extending arm 34 and an upwardly extending arm 35. The first mentioned arm 33 is provided at its forward end with a flange 36 having an elongated slot 37 for the passage of the shank 33 that carries the caster wheel, the slot 37 being of proper dimensions to permit rocking movement of the latter, while the flange 36 engages the head or bearing member 24. The upwardly extending arm 35 of the adjusting lever is connected by a rod or connecting member 38 with the evener 39 with which

the draft is in practice connected, said evener being connected with the tongue 15 in such a manner as to permit a longitudinal slideable movement thereof. It will be seen that 5 when draft is applied to the evener the lever L will be rocked, the forwardly extending arm 33 of said lever being depressed against the head or bearing member 24 with the result that the tongue will be lifted, thereby 10 relieving the necks of the draft animals of downward stress.

The tongue is pivotally connected by the member 21 with the binder frame H, and an upright 40 on said frame carries a tilting 15 lever 41 which is connected by a link 42 with the bracket member B for the purpose of tilting the binder frame with respect to the tongue in the usual manner. The binder frame H is supported for vertical adjustment 20 with respect to the axle 43 by means of pinions meshing with arcuate racks, one of said pinions being seen at 44 in engagement with an arcuate rack 45. Mounted in a convenient position on the binder frame, for instance, on the upright 40, is a guide pulley 46 over which passes a flexible element 47, one end of which is connected with the rearwardly extending arm 34 of the adjusting lever, while the other end is connected with 25 a collar 48 on the axle 43. It will be seen that when the binder frame is lifted with respect to the axle, the guide pulley 46 will likewise be moved in an upward direction, tensioning the connecting member 47 and 30 exerting a stress on the lever L, whereby the forward end of said lever will be depressed, causing the tongue to be lifted with respect to the supporting wheel or caster 27, thereby maintaining the binder frame in a level position which would not be possible if the tongue were permitted to remain stationary. 35

From the foregoing description taken in connection with the drawings hereto annexed, the operation and advantages of this 40 invention will be readily understood by those skilled in the art to which it appertains. The construction of the improved tongue truck is very simple and inexpensive, and it

may be readily installed on any binder of conventional construction on agricultural 50 machines of various kinds in connection with which it is designed to be used.

Having thus described the invention, what is claimed as new, is:—

1. A tongue having a vertical slit at its 55 rear end, a bracket member engaging said slit and secured by transverse bolts, said bracket member having laterally extending lugs, a rotary shank slideable in said lugs and having a head formed thereon, a caster 60 wheel carried by said shank, and a suitably supported lever having a slotted flange engaging the head of the shank whereby downward stress may be exerted on the wheel carrying shank to cause a corresponding lift- 65 ing stress upon the tongue.

2. A tongue having a vertical slit at its rear end, a bracket member engaging said slit and secured by transverse bolts, said bracket member having laterally extending 70 lugs, a rotary shank slideable in said lugs and having a head formed thereon, a caster wheel carried by said shank, a suitably supported lever having a slotted flange engaging the head whereby downward stress may be ex- 75 erted on the wheel carrying shank to cause a corresponding lifting stress upon the tongue, said lever having an upwardly ex- 80 tending arm, an evener connected with the tongue for longitudinal slideable movement, 85 and a connection between said evener and the upwardly extending arm of the lever.

3. A tongue, a vertically slideable rotary shank connected therewith, a caster wheel carried by said shank, an evener connected 85 with the tongue for longitudinal slideable movement, a lever having an arm engaging the wheel carrying shank and an upwardly extending arm, and a connection between the upwardly extending arm and the evener 90 whereby draft applied to the evener will rock the lever to produce a downward stress on the wheel carrying shank and a corresponding upward stress upon the tongue.

In testimony whereof I affix my signature. 95
THOMAS C. DUNCAN.
